UNITED STATES PATENT OFFICE.

SAMUEL B. WILLIAMS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 29, 1924. Serial No. 758,540.

This invention relates to telephone exchange systems, and more particularly to that class of telephone systems wherein automatic switching apparatus and automatic switching controlling apparatus are employed in the establishment of conversational connections.

It has been the practice heretofore in telephone systems wherein calling and called subscribers' lines are located in different offices, and wherein no direct trunks interconnect these offices, to employ so-called tandem switches located at an intermediate or tandem office. Systems of this character have been devised wherein an intermediate office may function both as a terminating office and as a tandem office. In such systems, apparatus at the intermediate office distinguishes the classes of calls undergoing completion. If the called line is located in the intermediate office, local switches are operated, whereas if the called line is located in a succeeding office, other classes of switches are operated. In such systems, it has been necessary to transfer the complete designation or a substantial portion thereof from the originating office to the intermediate office regardless of whether this intermediate office is to function as a terminating or as a tandem office.

It is an object of the invention, therefore, to enable an office which is adapted to function as a terminating office and as a tandem office to discriminate between the different classes of calls requiring extension prior to the reception of the line designation from the originating office.

A feature of the invention relates to a registering and impulse generating mechanism which automatically transmits a discriminating digit to a distant office prior to the transmission of the line designation.

Another feature of the invention relates to a common registering and controlling mechanism which is adapted to control the completion of local and tandem connections, the discrimination between the different classes of connections being accomplished prior to the registering of a line designation in said mechanism.

A still further feature refers to a telephone office wherein different types of registering and controlling senders are employed,

whereby seizure of one type of sender under certain conditions causes the seizure of another type of sender in the same office.

Other features and advantages of the invention not specifically mentioned will become apparent after a consideration of the following description and the appended claims.

Referring to the drawing,

Fig. 1, in the upper left corner, shows one of a number of subscribers' lines terminating in a coordinate line switch from which trunks lead to district switches, one of which is shown in the upper right portion of this figure. In the lower left portion of this figure is shown a coordinate sender selector switch, while in the lower right-hand portion are shown a district trunk connector and a district frame connector.

Fig. 2, in the upper portion, shows in comparative detail an interoffice incoming trunk, as well as an interoffice incoming selector switch. The lower left-hand portion of this figure shows a coordinate sender selector switch similar to switch 150; whereas the lower right-hand portion shows a trunk connector and a frame connector. The apparatus disclosed in Fig. 2 is located in an office which is distinct from that including the apparatus shown in Fig. 1.

Fig. 3, in the central portion, shows a tandem district selector switch located in the same office with switch 200. This figure also represents schematically a tandem sender selector, a tandem sender, an outgoing marker and various connecting devices.

Fig. 4 shows the impulse generating and controlling equipment of the sender located at the originating office. This figure also illustrates certain class relays.

Fig. 5 to the left and below the broken line shows a sender connector and a portion of an incoming marker. The remainder of this figure, illustrates a portion of an outgoing marker, and a schematic representation of a sender connector.

Fig. 6 shows the various registers located in the originating sender.

Fig. 7 shows an incoming sender.

Fig. 8 shows a general arrangement of the switching apparatus embodied in a preferred form for carrying out the invention.

Fig. 9 is a diagram showing the manner

in which the several sheets of the drawing should be organized.

General description.

- 5 The invention is shown as applied to telephone systems of the general character disclosed in the patent to S. B. Williams, No. 1,517,331, granted December 2, 1924, and also in the copending applications of S. B. 70
10 Williams and E. S. Gibson, Serial No. 645, 011, filed June 13, 1923; S. B. Williams and E. S. Gibson, Serial No. 722,215, filed June 25, 1924 and W. W. Carpenter, Serial No. 703,362, filed April 1, 1924. Reference may 75
15 be had to these applications for certain details of construction and operation of the various switches and connectors, as well as of the senders and markers referred to hereinafter. The line switch 100, district switch 160, incoming switch 200, tandem district switch 300, as well as the sender selector switches 150, 250 and 310 are of the coordinate type, such as shown and described in detail in the British patent to Western Electric Company, Ltd. No. 183,438, accepted 80
20 September 6, 1923 and also in the above-mentioned patent to Williams. The various connectors 170, 180, 230, 240, 500, 571, 340, 360 and 370 consist of groups of multi-contact relays which are adapted to be actuated by means of non-interfering start circuits.

35 Referring to Fig. 8 of the drawing, a description will now be given of the general arrangement and functioning of the switching apparatus embodied in a preferred form for carrying out the invention. It will be noted upon inspection that the drawing of Fig. 8 is divided into sections by means of broken lines. The apparatus to the left of the left-hand broken line is situated in an office which will be described hereinafter as the originating office. The apparatus shown between the broken lines is situated at a second office which is adapted to extend connections to local subscribers' lines and to extend connections from the first office to offices beyond. The rectangle to the right of the right-hand broken line represents one or more succeeding offices wherein subscribers' lines terminate.

40 For the purpose of securing relative simplicity in the drawing, the subscribers' lines, as calling lines, are shown as appearing in the first office but it will be readily understood that other subscribers' lines terminate in the intermediate and succeeding offices. It will be assumed, therefore, that the subscriber of line 801 has initiated a call, resulting in the automatic operation of line switch 800, whereby an idle trunk, as trunk 802, leading to the district switch 803, is seized. Coincident with the seizure of such a trunk, sender selector switch 804 is actuated, whereupon an idle sender, as 805, is

associated with the calling line. For the present, it will be assumed that the wanted line is located in the office represented between the broken lines. The calling subscriber having dialed the office code and numerical designation of the wanted line, the registers of the sender 805 are correspondingly set. As soon as the thousands digit is thus recorded in the sender, a connecting device, or sender connector 806 is actuated, 75 associating an idle marker 807 with the sender 805. The record of the office code is then transferred to corresponding registers in the marker 807 wherein it is translated to mark for selection a particular group of trunks 80 leading from the district switch 803 to the called office. The translation in the marker results in the setting of a preliminary or class of service registers in the sender 805. At the time the marker is associated, the frame connector 808 and trunk connector 809 are selectively actuated. Connector 808 associates the links of switch 803, before which trunk 802 appears, with testing equipment in the marker. Likewise, connector 809 associates 90 the test conductors of the marked group of trunks with the same testing equipment. As a result of this test, an idle link giving access to an idle trunk, as 811, is selected and the corresponding horizontal magnet is operated, thus establishing connection with the interoffice trunk.

When the trunk has been seized, the connectors 808, 809, marker 807 and connector 806 are released. The sender 805 remains engaged and having previously received certain class information as a result of the marker's translation of the office code, the sender now prepares itself for the transmission of series of code impulses. These class 105 indications in the sender not only indicate the necessity of sending code impulses but may also indicate that the called line is located in the same office to which the impulses are to be sent. It is to be noted that some 110 indication must be given to the recording sender at the office wherein trunk 811 terminates informing such sender that the called line is located in the same office therewith, since certain of the switches in this 115 office are adapted to extend trunk 811 through this office to succeeding offices. As soon as trunk 811 is seized, the incoming sender selector switch 812 is actuated and an idle incoming sender 813 is attached. Sender 813 comprises a number of registers, one of which acts as a discriminating register, the remaining registers recording the numerical portion of the called line designation. 125

130 The class information received by the sender determines the character of the impulses which are sent prior to the transmission of the line designation. Since the called line is located in the same office with 135

sender 813, a preliminary digit, for example the digit "0", is automatically transmitted from the class of service register in sender 805 prior to the transmission of the line designation. This "0" digit is then recorded on the discriminating register in sender 813 and the numerical record is completely transferred from sender 805 to sender 813. The sender connector 814 is thereupon actuated to associate an idle incoming marker 816 with sender 813 and the numerical record is transferred from the sender to the marker registers. The thousands digit determines the selection of a group of trunks including trunk 817 leading to a particular final switch 815, whereupon the line marker 818 is associated with the sender and the record of the hundreds, tens and units digits is transferred thereto from the sender 813. At this time, the connectors 822 and 823 also are operated. The record in the line marker results in the selective operation of the incoming and final switches 810 and 815, whereby connection is completed with the called line. During the connection, connectors 808, 809, 819, 821, 822, 823, 832 and 833, and sender selectors 804 and 812 and senders 805 and 813 are released together with the incoming marker 816 and the line marker 818.

Should the called subscriber's line be located in an office beyond and to which no direction trunks lead from the office in which line 801 is located, then the connection is extended over a trunk similar to trunk 811, terminating in an incoming switch as 810. In this case, however, the office containing switch 810 must function as a tandem office in order to complete the connection to the office beyond. Accordingly, prior to the transmission of impulses in accordance with the setting of the office code and numerical registers of sender 805, a preliminary digit in this case "1" is transmitted by means of code impulses to the preliminary register in sender 813. The digit 1 is recorded in sender 813 and serves to indicate to said sender that the call is of the tandem class. As soon as this preliminary digit is received, the impulse generating mechanism at the originating office is stopped, thus preventing the sending of further impulses to sender 813. The recording of the digit 1 at sender 813 also causes incoming switch 810 to be actuated, whereby a trunk 824 leading to a tandem district switch 820 is selected. Immediately that this trunk is seized, the connectors 814, 819, 821 and the incoming marker 816 are released and revert to common use. Sender 813 however, remains engaged. The seizure of trunk 824 also causes sender selector switch 826 to operate to associate an idle tandem sender 827 with the incoming trunk. The tandem sender having been thus attached, an indication is given to the

originating sender 805 which thereupon proceeds to transmit the complete designation of the wanted line through the sender 813 to the registers of the tandem sender 827. Meanwhile, the impulse receiving relays in the incoming sender 813 have been cut out of circuit and a pulse counting combination substituted therefor, so that when the complete number of impulses have been transmitted to the tandem sender, sender 813 and switch 812 may release. Upon the receipt of the office code and thousands digit by sender 827, connector 828 is actuated to associate an idle marker 829 therewith. The office code record is thereupon transferred from sender 827 to marker 829, wherein it is translated. At this time connectors 832 and 833 are also operated. The translation of the office code causes the tandem district selector switch 820 to seize one of a number of trunks as 831 leading to the called office. The seizure of this trunk causes connectors 832, 833, 828 and marker 829 to release, the tandem sender 827 remaining engaged. In the manner described in the copending application of S. B. Williams and E. S. Gibson Serial No. 645,011, filed June 13, 1923, the record of the wanted line is next transferred from the sender 827 to an incoming sender in the called office, resulting in the selective operation of incoming and final switches, and seizure of the called line.

Detailed description.

It will be first assumed that the subscriber at station 101 has initiated a call for the purpose of communicating with a subscriber whose line is located in a distant office to be reached without the use of tandem switching apparatus. When the calling subscriber removes his receiver from its switchhook, line switch 100 is actuated to extend the calling line to an idle district trunk 151, whereupon the conductor 152 is grounded causing the energization of relay 102. The operation of relay 102 in turn causes the sender selector switch 150 to be actuated whereby an idle sender such as shown in Figs. 4 and 6 is associated with the calling line. As soon as a sender has been thus associated, and with the start relay 102 operated, a record is made in the sender of the group of district switches wherein trunk 151 terminates. The circuit for this purpose may be traced from battery through the winding and normal contacts of relay 414, right contacts of relay 407, conductor 456, contacts of switch 150, inner armature and front contact of relay 102 to ground through the cross connection block 117. Relay 414 relates to the connecting device 170 which is capable of associating any district switch in the group including switch 160, with the marker shown in Fig. 5. Relay 414 immediately locks through its winding and locking contact, to conductor

453, which was grounded when the sender was seized. A short interval after the association of the sender, the start relay 102 is released, but the connection of the sender with the trunk 151 is maintained by the continued energization of a horizontal magnet as 157. The tip and ring conductors of the calling line are now extended through contacts of switch 150 to the impulse receiving mechanism 400. The calling subscriber thereupon is notified by a characteristic signal that the circuits and apparatus are in readiness for the reception of series of dial impulses. For the purpose of description it will be assumed that the code of the office in which the called line is located is GER. In dial impulses this code would be represented by series of 4, 3 and 7 impulses, respectively. The first series of 4 impulses having been transmitted by the calling subscriber is recorded upon the counting relays of the receiving device 400. For a detailed description of the manner in which the foregoing operations are effected, reference may be had to the patent to S. B. Williams, No. 1,517,331, issued December 2, 1924.

When the sender is attached to the calling line as mentioned above, ground is extended through the contacts of relays 415 and 601, to battery through the winding of relay 602. Relay 602 is immediately locked by means of a circuit which is completed through the winding and locking contact thereof, conductor 657, winding of relay 415, to control ground. Relay 415 does not operate in this circuit however, because of the existence of the shunt produced by the previously traced operating circuit of relay 602. With relay 602 operated the windings of the relays of register 610 are connected to the impulse receiving mechanism 400, and since the first letter of the office code has been assumed to be G, conductor 653 is grounded, thus causing the operation of register relay 603. Relay 603 immediately locks to the grounded conductor 652, and extends this same grounded conductor through the left outer contacts of relay 603 to battery through the winding of relay 601 which operates and also locks to conductor 652. Relay 601 in operating opens the operating circuit of relay 602 removing the shunt from around the winding of relay 415. Relay 415 thus operates in series with relay 602.

In the manner described in detail in the above mentioned patent to S. B. Williams, No. 1,517,331, the operation of relay 415 at this time causes the release of the operated counting relays corresponding to the first series of impulses transmitted, whereupon relays 415 and 602 in turn are released. With relay 415 normal a circuit is completed from battery through the winding of relay 604, back contacts of relay 609, front contacts of relay 601, conductor 451, contacts of relay 415 to ground. Relay 604 is similar in function to relay 602 and serves to connect the counting relays 400 to the relays of register 620. Relay 604 also locks in series with relay 415 which fails to operate because of the shunt circuit which has already been traced. The second series of impulses corresponding to the letter E, as recorded on the counting relays, results in the grounding of conductors 654 and 655 whereby register relays 605 and 606 are operated. Relays 605 and 606 immediately lock to the grounded conductor 652. A circuit is thereupon closed for relay 609 which also locks to conductor 652 and removes the shunt from around the winding of relay 415 in a manner similar to that described in connection with relay 601. Thus relays 604 and 415 are locked in series to the grounded conductor 652. Relay 415 in operating, as mentioned hereinbefore, causes the release of the operated counting relays, whereupon both relays 604 and 415 release.

Relay 612 is now operated over a circuit which is completed through the back contacts of relay 611, front contacts of relays 609 and 601 to conductor 451. The third series of impulses corresponding to the letter R are now received by the counting relays, causing conductors 651 and 655 to be grounded and resulting in the operation of relays 607 and 608 which lock. Relay 611 is now operated and brings about the actuation of relay 415 in series with relay 612, whereupon the counting relays, and relays 415 and 612 are successively deenergized. In a manner similar to that above described succeeding series of impulses as received by the counting relays are transmitted to succeeding numerical registers the first of which, namely the thousands register, is shown in comparative detail, while the remaining numerical registers are represented by the dotted rectangle 670. When relay 611 operates it closes a circuit traceable from battery through the winding of relay 407, conductor 463, contacts of relay 611 to the grounded conductor 652. Relay 407 operates in this circuit and serves as an indication to the sender that the office code portion of the called line designation has been registered, and the sender is now in readiness to be associated with an idle switch controlling marker.

It will be assumed that the marker shown to the left of, and below the broken line of Fig. 5 is idle, when relay 407 operates. A circuit is therefore completed from battery through the left winding of relay 501, conductor 454, back contacts of relay 408, left contacts of relay 407 to ground. Relay 501 is a start relay and functions to bring about the selective operation of connector 500 by first causing the operation of multi-contact relay 502. Relay 503 is also actuated in the manner described in detail in the ap-

application of W. W. Carpenter, Serial No. 703,362 hereinbefore referred to. With relays 502 and 503 operated, registers 610, 620 and 630 are associated with corresponding registers 510, 520, 530 in the marker.

Transfer of record from the sender to the marker and the selection of an outgoing trunk.

- 10 As soon as the connecting device 500 has operated, the conductor 454 is extended by means of contacts of this connector to battery through the winding of marker ground control relay 504. Since relay 603 of the 15 first register is operated a circuit is completed for operating relay 505. This circuit may be traced from battery through the winding of relay 505, contacts of connector 500, conductor 757, right outer contacts of 20 relay 603, conductor 459, returning through contacts of connector 500, thence through the left contacts of relay 506 to ground at the armature of relay 504. Since relays 605 and 606 of the second register are operated 25 similar circuits are closed for corresponding relays 507 and 508 in the marker. Likewise circuits may be traced for relays 509 and 511 corresponding to the operated relays 607 and 608 of the third sender register. The 30 record of the office code having thus been transferred to the marker, the translating device 550 is selectively actuated in accordance with this record to cause conductors 551, 552 and 553 to be grounded. The 35 grounding of conductor 551 causes the operation of relay 512. Relay 512 closes obvious operating circuits for relays 416, and 429 in the sender. The grounding of conductor 552 causes relay 417 to operate. 40 These relays upon operating close locking circuits which are completed to the grounded conductor 453. The operation of relays 416, 417 and 429 serves to indicate to the sender the class of call requiring extension, 45 so that the said sender may subsequently adjust itself for controlling the sending of code impulses to the recording sender at a succeeding office. The actuation of translator 550 also causes conductor 553 to be 50 grounded whereby relay 513 is operated. Relay 513 is individual to the group of trunks leading from district switch 160, including trunk 161, which leads in the direction of the called office. Relay 524 is another 55 group relay and may be operated when a different office code is recorded on the registers 510, 520, etc. Since there may be a plurality of district switches it becomes necessary to distinguish to the marker the particular switch wherein the trunk 151 terminates. Accordingly frame connector start 60 relay 103 is operated in a circuit traceable from battery at the contact of relay 503, conductor 557, winding of relay 103, conductor 558, contacts of connector 500, right 65

front contact of relay 414, conductor 459, contacts of connector 500, to ground at an armature of relay 504. Relay 103 in turn brings about the actuation of a common relay 104, whereby ground is extended 70 through the contacts of this latter relay to operate multi-contact relay 105.

It is to be observed that the vertical magnet 106, which controls the vertical row of contacts in switch 160 wherein trunk 151 75 terminates, was operated subsequent to the association of the marker with the sender. The circuit for operating magnet 106 may be traced from battery through the winding thereof, through contacts of relays in the 80 trunk circuit 151 (not shown), outer armature and back contact of relay 102, contacts of switch 150, conductor 457, conductor 458, contacts of connector 500, conductor 559, contacts of relay 105, returning thence to 85 conductor 459, to ground at an armature of relay 504. This same ground for operating magnet 106 is extended through the lower contacts thereof and thence to battery 90 through the winding of multi-contact relay 95 105. The operation of relays 105 and 107 associates, with the marker testing equipment 570, a conductor from each of the horizontal links and a conductor from each of the windings of the corresponding horizontal 100 magnets in switch 160. When relay 103 operated as mentioned hereinbefore ground was extended through the contacts thereof over conductor 461, left outer contacts of relay 513, conductor 462, to battery through 105 the winding of relay 108. Relay 108 is associated with the trunk connecting device 180 and acts as a start relay for causing the selective operation of this connector. Relay 108 also causes the actuation of relay 109 as described in the above mentioned 110 application of W. W. Carpenter, Serial No. 703,362, whereby multi-contact relay 111 is subsequently operated. With relay 111 operated, a circuit is closed for operating the trunk vertical magnet 114 which controls the vertical row of contacts in which the selected group of interoffice trunks terminates. The circuit for this purpose may be traced from battery through the winding of 115 magnet 114, contacts of relays 107 and 105, conductor 162, left inner contacts of relay 513, conductor 562, contacts of relay 111, returning thence to ground. This same ground is extended through the contacts of relay 108 over conductor 563, right contacts of relay 513, conductor 564, to battery 120 through the winding of relay 112. The operation of relays 111 and 112 associates the test conductors of the trunks in the selected group with the marker test relays 570. In the manner described in detail in the above mentioned application of W. W. Carpenter, the marker test relays 570 determine an idle 125 cross point through switch 100. This cross 130

point includes a link, for example link 113, before which appears an idle interoffice trunk as 161. The horizontal magnet 116 corresponding to this idle cross point is 5 thereupon energized and the trunk 161 is seized.

- The marker having completed its function in the controlling of the selection of an interoffice trunk is now released and may 10 revert to common use. The release of the marker may be initiated by the operation of relay 408. The manner in which the marker controls the selection of an outgoing trunk and the manner in which the said marker is 15 released upon the seizure of said trunk is fully described in the above mentioned application of W. W. Carpenter, Serial No. 703,362 to which reference may be had for a detailed description of operation of the 20 connectors 170 and 180, as well as of the switch 160, these having been described herein in a comparatively general manner.

When relay 408 operates, subsequent to the seizure of trunk 161, a circuit is completed from battery through the winding of 25 relay 401, left contacts of relay 416, right contacts of relay 408, left contacts of relay 407 to ground. Relay 401 immediately locks to the grounded conductor 453. The actuation of relay 401 prepares the sender for the transmission of code impulses to the distant office. Relay 401 also completes a circuit from battery through the right winding of relay 202, right contacts of 30 relays 201 and 204, thence over the tip side of trunk 161, through contacts of switch 160, tip side of trunk 151, contacts of switch 150, conductor 457, left inner contacts of relay 401, right contacts of relay 419, winding of relay 409, left contacts of relay 419, left outer contacts of relay 401, conductor 456, contacts of switch 150, over the ring side of trunk 151, through contacts of 35 switch 160, over the ring side of trunk 161, left contacts of relays 204 and 201, to ground through the left winding of relay 202. Relays 202 and 409 operate in this 40 circuit. Relay 202 closes an obvious operating circuit for relay 203. Relay 203 is a 45 relay similar to relay 102 and when actuated causes the sender selector switch 250 to associate an idle incoming sender, such as shown in Fig. 7, with the incoming trunk 161. With relay 409 operated, a circuit is 50 completed from battery through the winding of relay 418, contacts of relay 409, back contacts of relay 420 to ground over conductor 453. Relay 418 also closes a holding circuit which is completed through the 55 winding of relay 419, and thence to ground as above traced by means of the outer contacts of relay 418. Relay 419 is shunted by the operating circuit described for relay 418 and does not operate at this time. When 60 the sender at the distant office has been asso-

ciated with the trunk, ground is returned over the conductor 752, thence through contacts of switch 250 to operate relay 204. Relay 204 causes the release of both relays 202 and 409. The release of relay 409 removes the shunt from around the winding of relay 419 and this relay operates in series with relay 418. If the thousands digit has been recorded, then relay 614 is operated, whereupon a circuit is completed from battery through the right winding of relay 423, left outer back contacts of relay 424, left inner contacts of relay 614, conductor 661, front contacts of relay 418, back contacts of relay 420, to the grounded conductor 453. Relay 423 connects ground through its inner right contacts, left outer back contacts of relay 411, right outer contacts of relay 411, right outer contacts of relay 421, left outer contacts of relays 413 and 404, winding of relay 403, to battery at the contacts of relay 402. Relay 403 operates and closes an obvious energizing circuit for relay 404. Relay 404 closes a locking circuit for itself which may be traced from battery through the left winding and left locking contact of said relay, to ground through the left outer armature and back contact of relay 411. Relay 404 by means of its right middle contacts provides a locking circuit for relay 423 which is completed through the left winding and locking contact of relay 423. When relay 404 operated, it also closed a circuit for operating the connecting relay 623 of the preliminary register relay 625. The circuit for this purpose may be traced from battery through the winding of relay 623, right back contacts of relay 627, right inner contacts of relay 429, contacts of relay 426, to ground at the middle contacts of relay 404. Relay 623 locks in series with the winding of relay 426 to the same ground. However, the operating circuit described for relay 623 acts as a shunt around the winding of relay 426 and this relay fails to operate. The operation of relay 404 also causes the release of relay 403 whereupon the impulse timing relays 412 and 413 are started in operation. The circuit for operating relay 412 may be traced from battery through the winding of relay 412, left inner back contacts of relay 413, right outer contacts of relay 404, left inner contacts of relay 403, to ground at an armature of relay 419. When relay 412 has attracted its armatures, it completes a circuit from battery through the winding of relay 413, thence through the left inner front contacts of relay 412 to ground as above traced. Relay 413, extends this same ground through its right contacts, thus shunting the winding of relay 412 which begins to release. When relay 412 has retracted its armatures completely, the above traced circuit for relay 413 is opened

and this relay begins to release. The characteristics of relays 412 and 413 are such that their armatures are attracted and retracted in a relatively slow manner. This 5 cycle of operation and release of relays 412 and 413 is continued until all the required impulses have been transmitted. When relay 412 first operates, a circuit is closed from battery through the left winding of relay 10 411, winding of relay 421, inner left back contacts of relay 411, to ground at the left outer contacts of relay 412. Relay 421 operates in this circuit, but relay 411 being marginal fails to operate. When relay 421 15 operates, it completes a circuit through the left winding of relay 411, winding of relay 421, right winding of relay 411, right inner contacts of relay 421 to the grounded conductor 453, relay 411 remains shunted and 20 fails to operate. When relay 412 releases during the first cycle, the shunt is removed from the windings of relay 411 and this relay operates in series with relay 421.

Prior to the completion of the first of 25 operation and release of relays 412 and 413, and subsequent to the deenergization of relay 412, a circuit is completed from battery at the contacts of relay 402, winding of relay 406, left inner contacts of relay 421, 30 left inner back contacts of relay 412, right outer contacts of relay 404 to ground through contacts of relays 403 and 419. Relay 406 locks through its winding and locking contacts, thence through the left outer armature and front contact of relay 411, to 35 ground at the right inner contacts of relay 423. The operation of relay 406 opens the impulse circuit and reverses the connection of the tip and ring conductors of the trunk with the impulse mechanism. It will be 40 noted that when relay 411 operated, a circuit was completed from battery through the right winding of relay 422, winding of relay 427, right back contacts of relay 422 45 to ground at the right inner contacts of relay 411. Relay 427 operates in this circuit but relay 422 receives insufficient current and remains normal. During the first impulse period no code impulse is transmitted to 50 the distant office.

Relays 412 and 413 undergo another cycle of operation and release for the purpose of timing the second impulse period. When relay 412 operates at the beginning of the 55 second cycle, a direct locking circuit is completed through the left winding of relay 411, thus shunting relay 421 which releases. During this period, the operation of relay 406 closes a circuit from battery through 60 the high resistance 671, conductor 672, left outer front contacts of relay 406, left outer back contacts of relay 403, left outer contacts of relay 401, thence by means of contacts of switches 150 and 160, to the ring 65 conductor of trunk 161, through contacts of

switch 250, conductor 753, right outer contacts of relay 702, back contacts of relay 703, windings of relays 705, 708 and 709 in series, right inner contacts of relay 702, right back contacts of relay 701, conductor 759, 70 returning by means of switch 250 to the tip conductor of trunk 161, through contacts of switches 160 and 150, inner left contacts of relay 401, right back contacts of relay 403, inner right front contacts of relay 406, left 75 outer contacts of relay 423 to ground at the armature of relay 419. The direction of flow of the current in this circuit is such as to cause the operation of relay 708, but because of the inclusion therein of the high 80 resistance 671, marginal relay 705 remains normal. Relay 708 extends the grounded conductor 751 through the contacts of the said relay, right back contacts of relay 707, right winding of relay 710, to battery 85 through the right winding of relay 707. Relay 710 operates in this circuit but relay 707 receives insufficient current to cause the energization thereof. Relay 710 completes a 90 circuit from battery through the winding of relay 712, left outer back contacts of relay 714, left front contacts of relay 710 to the grounded conductor 751. Relay 712 operates and closes a circuit through its winding 95 and the winding of relay 714, thence through the left outer front contacts of relay 712 to ground as above traced. Relay 714 is shunted however, and does not operate in this circuit. Prior to the end of the second impulse period, relay 412 releases thus opening the holding circuit of relay 411 which 100 also releases. Relay 411 in turn brings about the release of relay 406, thus opening the impulse circuit and causing relay 708 at the distant office to retract its armatures. 105 The release of relay 411 removes the shunt from around the winding of relay 422 and this relay now operates in series with relay 427. At the termination of the second impulse period, relay 413 retracts its armature. 110 Relay 404 having released when relay 412 retracted its armatures during the second period, a circuit is now closed for relay 403 by means of a path which has been hereinbefore traced. Relay 403 grounds both sides 115 of the impulse circuit for the purpose of discharging electrically, the metallic conductors thereof, and also closes an obvious circuit for relay 404 which locks over a circuit hereinbefore traced. Relay 404 in turn causes the release of relay 403 and the impulse circuit is again prepared. When relay 708 released, as described above, the shunt was removed from around the winding of relay 707 and this relay operates in series with relay 710. Relay 710 remains operated in this circuit so that the shunt is maintained around the winding of relay 714. When relay 422 operates as above described, a circuit is closed from battery 120 125 130

through left winding of relay 428, winding of relay 405, left back contacts of relay 428, left front contacts of relay 422, left contacts of relay 402, to ground at the left back contact of relay 421. Relay 405 operates but relay 428 being marginal does not operate. Since relay 406 is normal during this period however, the impulse circuit is open and the recording relays at the distant office are not affected.

The operation of relay 412 during the third impulse period causes relay 421 to re-operate, but relay 411 is shunted and remains normal. Prior to the end of the third period, when relay 412 releases, it opens the shunt around the winding of relay 411, which operates in series with relay 421. Relay 411 completes a direct locking circuit to battery through the left winding of relay 422, thus shunting relay 427 which releases. The operation of relay 421 at this time opens the shunt from around the winding of relay 428 which now operates in series with relay 405. At the end of the third period with relays 412 and 413 normal, a circuit is closed for operating relay 406 for purposes hereinbefore described. Relay 406 locks, and relays 412 and 413 undergo a fourth cycle of operation and release. The operation of relay 412 at the beginning of this cycle causes the release of relay 421 by shunting the same. Relay 421 in turn closes a direct locking circuit for relay 428, causing relay 405 to release. Since relay 406 is operated, the previously traced circuit, including the high resistance 671 and relays 705, 708 and 709, is again completed resulting in the re-operation of relay 708. Relay 708 upon operating closes a direct locking circuit for relay 707 and shunts relay 710 which releases. Prior to the termination of the fourth period when relay 412 has released, the holding circuit of relay 411 is opened and this relay also released in turn, causing the release of relay 422. Relay 422 opens the locking circuit of relay 428 which restores to normal. With relays 411 and 412 normal, relay 404 releases, and when relay 413 releases at the end of the fourth period, a circuit is closed for energizing relay 403 as described hereinbefore. Relay 403 opens the impulse circuit and causes the line conductors to be discharged. The impulse mechanism is in readiness to transmit impulses corresponding to the digit recorded on the thousands register 640. It will be noted however, that at the end of the fourth period as described, when the impulse circuit is opened by relay 403, relay 708 at the distant office releases, thus opening the locking circuit of relay 707 which also releases. Relay 707 removes the shunt from around the winding of relay 714 which operates in series with relay 712 to the grounded conductor 751.

When relay 427 operated, as above described, a circuit was completed from battery through winding of relay 627, right outer contacts of relay 427 to ground over conductor 453. Relay 627 immediately locks to the ground conductor 652. The operation of relay 627 in this circuit removes the previously described shunt circuit from around the winding of relay 426 which operates in series with relay 623. When relay 404 releases at the end of the fourth impulse period, this locking circuit is broken, whereupon 623 and 426 release. Relays 412 and 413 undergo four more cycles of operation and release for the purpose of timing the impulses corresponding to the thousands digit. Relay 404 operates as hereinbefore described and closes a circuit for relay 616 traceable from battery through its winding, back contacts of relay 626, outer front contacts of relay 425, outer front contacts of relay 629, 634 and 632, right inner front contacts of relay 424, right back contacts of relay 625, front contacts of relay 627, conductor 673, front contacts of relay 429, to ground through contacts of relay 426 and 404. Relay 616 locks in series with the winding of relay 426. Relay 426 however is shunted and remains normal. Relay 616 associates the thousands register 640 with the impulse circuit.

It will be assumed that the thousands digit of the called line designation is "1". Accordingly, relay 617 is operated and during the first impulse period, a circuit is completed from battery through the high resistance 671, front contacts of relay 617, left outer contacts of relay 626, right normal contacts of relay 424, right outer front contacts of relay 423, left back contacts of relay 405, right normal contacts of relay 406, right back contacts of relay 403, inner front contacts of relay 401, thence by means of contacts of switch 150 to the tip conductor of trunk 151, through contacts of switch 160 to the tip conductor of trunk 161, contacts of switch 250, conductor 759, thence through the windings of relay 705, 708 and 709 in series, returning by means of switches 250, 160 and 150 through the outer front contacts of relay 401, left outer back contacts of relay 403, left normal contacts of relay 406, left front contacts of relay 423, to ground at the armature of relay 419. The direction of flow of current in this circuit is of such a nature as to cause relay 709 to operate, but because of the inclusion of resistance 671, marginal relay 705 remains normal. With relay 709 operated, a circuit is completed from battery through the winding of register relay 715, left back contacts of relay 719, left inner front contacts of relay 712, right back contacts of relay 710, contacts of relay 709 to ground over conductor 751. Relay 715 immediately locks to the grounded conductor 130

751. Since relay 618 of the thousands register is normal, then no impulse is sent to the distant office, during the second period, to operate the corresponding relay 716. However, during this second impulse period, since relay 406 is operated, a circuit is closed from battery through the high resistance 671, left outer front contacts of relay 406, left outer back contacts of relay 403, thence over the 10 ring side through the impulse receiving relays at the distant office returning thence over the tip side of the impulse circuit through the left inner contacts of relay 401, right outer back contacts of relay 403, right inner front contacts of relay 406 to ground through the left outer front contacts of relay 423 as hereinbefore traced. The polarity of the current in this circuit causes relay 708 alone to operate. Relay 708 completes a circuit from battery through the winding of 20 relay 719, left back contacts of relays 720 and 713, left outer front contacts of relay 714, left outer front contacts of relay 710, contacts of relay 708, to the grounded conductor 751. Relay 719 operates in this circuit but relay 720 being shunted remains normal. During the third and fourth impulse periods, no numerical impulses are sent, since register relays 619 and 621 are 25 normal. During the fourth impulse period, however, the above traced circuit including the high resistance 671 is closed, causing relay 708 to operate. Relay 708 by closing a direct locking circuit for relay 707 causes relay 710 to release as hereinbefore described, and at the end of the fourth period when the impulse circuit is opened by relay 403, relay 35 708 releases. The release of relay 708 in turn causes the release of relay 707 which removes the shunt from around the winding of relay 720. Relay 720 now operates in series with relay 719. The operation of relay 720 transfers the control of the impulse receiving mechanism of Fig. 7, to the second 40 or hundreds register 730. In the manner described in detail in the above mentioned patent to S. B. Williams, No. 1,517,331, the record on the hundreds, tens and units registers 670 of the sender of Fig. 6, is transmitted by means of impulses to cause the operation of corresponding relays in registers 730, 740 and 750. When register 750 has been 45 positioned, relay 758 operates. The operation of relay 758 extends the grounded conductor 751 through the right front contacts of said relay to battery through the left winding of relay 514. Relay 514 is a start relay similar to relay 501 and when energized brings about the operation of the connecting device 571 (similar to connecting device 500), whereby an incoming marker which is partly shown in the upper right hand corner of Fig. 5, is associated with the 50 sender of Fig. 7. When the device 571 is completely operated, conductor 751 is ex-

tended therethrough, causing the operation of marker ground control relay 522. In the manner described in detail in the above mentioned application of W. W. Carpenter, Serial No. 703,362, the marker controls the selective 70 operation of the incoming switch 200, whereby a trunk such as trunk 262 is seized. Trunk 262 is one of a number of trunks which lead to a final selector switch as 260, which has access to called lines in the same office, where- 75 in switch 200 is located. For a detailed description of the manner in which the connection may be completed to the called line 263 by means of switches 200 and 260 reference may be had to the above mentioned applica- 80 tion of W. W. Carpenter, Serial No. 703,362.

Extension of a connection involving an intermediate office as a tandem point.

It will now be assumed that the number 85 as dialled by the subscriber at station 101 is that of a line located in the office represented schematically by the rectangle 350. It will be further assumed that there are 90 no trunks directly connecting the calling 95 and called offices. In this instance, the recording of the office code on the sender registers 610, 620 and 630 and the subsequent transference of the record to the marker registers 510, 520 and 530 as hereinbefore described, will cause conductors 553, 554 and 555 to be grounded. The grounding of conductor 555 causes the operation of relay 516 whereby the class relays 416, 424, and 425 are operated. As a result of 100 the grounding of conductor 554, the preliminary register relay 625 is operated. Relay 625 on operating extends ground through its left outer front contacts to battery through the winding of relay 429. Relays 429 and 625 also lock to the grounded conductor 652. 105

It will be assumed that the called office is reached by one of the trunks in the group controlled by relay 513 which is operated 110 as a result of the grounding of conductor 553. The operation of class relay 424 serves to indicate to the sender that the called office is to be reached by switching apparatus at the intermediate office as hereinbefore described so that the said sender may subsequently adjust itself for the controlling of the switching devices at succeeding offices. In this case, the controlling 115 of switch 160, to seize an interoffice trunk is accomplished in a similar manner to that already described in connection with the seizure of trunk 161. 120

For the purposes of description, it will be assumed that the line designation as 125 recorded on registers 610, 620 and 630, results in the seizure of trunk 161 whereupon the marker shown in Fig. 5 as well as the sender connector 500, frame connector 170 and trunk connector 180 are released. 130

Prior to the release of the marker, relay 408 operates as hereinbefore mentioned, causing relay 401 to operate and lock. Relay 401 in turn causes the operation of relay 409 in series with relay 202 at the distant office. Relay 203 is thereupon actuated and causes switch 250 to associate a sender such as shown in Fig. 7, with trunk 161. As hereinbefore described, in detail, when the 10 sender has been associated, relays 202 and 409 release, whereupon relay 418 operates in series with relay 419. The circuits are now in readiness for the transmission of impulses from the sender of Fig. 4 to the sender 15 of the distant office. In this case, however, register relay 625 is operated, and the impulses sent, prior to the transmission of the first digit of the office code, are of such a nature as to indicate to the distant sender 20 that the called line is not located in the same office therewith and that the said office must function as a tandem point. Accordingly, prior to the transmission of the office code, the operation of relay 625 causes impulses corresponding to the digit "1" to be sent from the originating office to the office wherein trunk 161 terminates. As soon as the thousands digit has been recorded on register 640 and the marker has released, a 25 circuit is completed from battery through the right winding of relay 423, right front contacts of relay 425, left inner contacts of relay 626, right front contacts of relay 614, right front contacts of relay 418, back contacts of relay 420, to the grounded conductor 453. Relay 423 immediately locks through its left winding to the same grounded conductor. The operation of relay 423 brings about the successive operation of relay 403 and 404 as hereinbefore described, whereupon the timing relays 412, and 413 begin their cycles of operation and release. During the first impulse period, a circuit is completed from battery through the high 40 resistance 671, right inner front contacts of relay 625, left back contact of relay 627, right outer front contacts of relays 424 and 423, left back contacts of relay 405, right normal contacts of relay 406, thence over the tip side of the impulse circuit to ground as hereinbefore traced. The direction of flow of current in this circuit is of such a nature as to cause the operation of relay 709 alone. Relay 709 completes a circuit from battery through the winding of relay 711, left inner back contacts of relay 712, right back contacts of relay 710 to ground through the contacts of relay 709. Relay 711 immediately locks to the grounded conductor 751. Relays 711 and 713 form a preliminary or class of service register corresponding to the preliminary register 50 in the sender of Fig. 6. Relay 711 extends grounded conductor 751 through its right outer contacts to battery through the winding of relay 713. When therefore relay 427 operates at the end of the first period as hereinbefore described, it completes a circuit for operating relay 627. This circuit may be traced from battery through the winding of relay 627, right outer contacts of relay 427 to the grounded conductor 453. Relay 627 locks to the same grounded conductor and breaks the original energizing circuit of relay 623 which now remains locked in series with relay 426, the latter relay operating. Relays 412 and 413 undergo three more cycles of operation and release as hereinbefore described. During the second period the circuit hereinbefore traced is completed from battery through the high resistance 671, thence over the ring side of the impulse circuit, conductor 753, outer back contacts of relay 702, windings of relays 705, 708 and 709, returning thence over the tip side of the impulse circuit to ground as already traced. Relay 708 operates and completes a circuit for relay 710. Relay 710 completes the circuit for operating relay 712 which locks in series with relay 714. Relay 714, however, remains normal. When relay 708 releases upon the opening of the impulse circuit after the third period, relay 707 operates in series with relay 710, relay 714, however, still being shunted. At the end of the fourth period, the circuit above traced is again completed through the winding of relay 708, which reoperates and shunts relay 710, the latter relay releasing. When the impulse circuit is opened at the end of the fourth period, relay 708 releases, in turn, releasing relay 707. Relay 714 now operates in series with relay 712 to the grounded conductor 751. Relay 714 in turn operates relays 701 and 703 which disconnect the receiving relays 705, 708 and 709 and prepare a new impulse circuit which will be described hereinafter. At the termination of the fourth impulse period, relays 404 and 427 release, thus opening the holding circuit of relays 623 and 426 which also release. 55 Relay 403 now operates to cause the energization of relay 412 as hereinbefore described. Relay 403, in turn, operates relay 404 which locks. A circuit is now closed from battery through the winding of relay 420, right back contacts of relay 410, right outer front contacts of relay 625, right front contacts of relays 627 and 429, contacts of relay 426, to ground at relay 404. Relay 420 in operating causes release of relays 418 and 419. Relays 412 and 413 undergo three more cycles of operation and release but no impulses are sent to the distant office because relay 419 is normal. Relay 420 completes 60 65 70 75 80 85 90 95 100 105 110 115 120 125 130

an obvious operating circuit for relay 410 which upon operating, opens the energizing circuit of relay 420 which begins to release. Relay 410 however is locked to the grounded conductor 453. Relay 420 however maintains its armatures in their attracted position for an appreciable interval.

At the end of the fourth impulse period 10 relays 404, 412, 413, 422 and 427 release as above described, whereby the original operating circuit of relay 423 is broken and this relay retracts its armatures thus preventing further operation of the timing relays 412 and 413. When relay 711 operated as above 15 described it extended grounded conductor 751 through its left inner contact, contacts of relay 704, to battery through the left winding of relay 514 which as hereinbefore mentioned causes the sender connector 571 to associate an idle marker with the incoming 20 sender. With the connector 571 operated, ground is extended over conductor 751 to battery through the winding of ground control relay 522. Relay 521 is now operated by 25 means of a circuit which may be traced from battery through the winding of said relay, contacts of connector 571, conductor 755, left outer front contacts of relay 711, returning through contacts of connector 571 to ground 30 at an armature of relay 522. Relay 521 in turn closes an obvious energizing circuit for relay 523. Relay 523 is a relay similar in function to relay 513 but is individual to a group of trunks leading out of switch 200 to 35 a tandem district selector switch such as 300. In the manner described in detail in the above mentioned application of W. W. Carpenter, Serial No. 703,362, relay 206 is energized resulting in the operation of multi-contact relays 207 and 208 thereby associating the links of switch 200 with the marker test relays 580. Relay 206 completes a circuit traceable from battery through the winding of relay 209, right outer front contacts of 40 relay 523, to ground through the contacts of relay 206. A short interval later, relay 211 is energized whereupon multi-contact relay 212 is actuated over an obvious circuit. Multi-contact relay 213 is also energized at this 45 time by means of ground extended through the outer contacts of relay 209, thence through the left inner contacts of relay 523 to battery through the winding of relay 213. Relays 212 and 213 associate the test conductors of the group of trunks, to which relay 523 is individual, with the marker test 50 relays 580. It will be noted that vertical magnet 216 was operated subsequently to the seizure of trunk 261, whereas vertical magnet 217 is now energized by means of a circuit 55 traceable from battery through the winding of said magnet, contacts of frame connector 230, left outer contacts of relay 523, contacts of trunk connector 240 returning to ground 60 through the contacts of relay 209.

It will be assumed that link 214 and trunk 264 are simultaneously idle, then the particular one of the test relays 580 corresponding to this idle crosspoint remains normal and as described in the above mentioned application of W. W. Carpenter, Serial No. 703,362, the corresponding horizontal magnet 218 is energized. A short interval after magnet 218 is operated, relays 526 and 527 are actuated and serve to release the marker, the 75 sender connector 571 and the connectors 230 and 240. The sender shown in Fig. 7 is not released however at this time.

As soon as the connection is completed with trunk 264 the sleeve conductor thereof is grounded resulting in the operation of relay 302. Relay 302 is similar in function to relays 102 and 203 and when energized causes the sender selector switch 310 to operate to associate a tandem sender 320 with the extended calling line. The sender 320 now awaits the receipt of code impulses from the calling office whereby the complete designation of the wanted line including the office code and numerical portions thereof is transferred from the registers of the sender shown in Fig. 6 to the tandem sender 320.

When switch 200 operated a circuit was completed from battery through the right contacts of relay 303, thence over the tip side of trunk 264 through contacts of switch 200, contacts of switch 250, front contacts of relay 701, returning through contacts of switch 250, over the tip conductor of trunk 161, contacts of switches 160 and 150, left inner contacts of relay 401, right back contacts of relay 419, winding of relay 409, left contacts of relay 419, left outer contacts of relay 401, returning over the ring side of trunks 161, contacts of switch 250, conductor 753, outer back contacts of relay 702, inner front contacts of relay 703, winding of relay 706, conductor 756, contacts of switch 250, ring conductor of trunk 264 to ground at the left contacts of relay 303. Relay 706 does not operate because of the polarity of the current in this circuit. When relay 420 has completely retracted its armatures, the circuit hereinbefore traced is completed for operating relay 418, and when the sender at the tandem office has been attached to trunk 264, relay 303 is energized thus causing the release of relay 409 at the originating office. The release of relay 409 causes relay 419 to operate in series with relay 418. With relay 419 operated a circuit is completed from battery through the right winding of relay 423, right contacts of relay 425, left inner contacts of 626, left front contacts of relay 614, front contacts of relay 418 to ground through the back contacts of relay 420. Relay 423 completes an operating circuit for relay 403 which in turn causes relay 404 to operate and lock; in turn closing a locking circuit for relay 423. With relay 404 op- 120 125 130 135 140 145 150 155 160 165 170 175 180

erated, a circuit is closed from battery through the winding of relay 628, right outer back contacts of relay 632, conductor 481, left outer front contacts of relay 429, right 5 front contacts of relay 410, right outer front contacts of relay 625, right front contacts of relays 627 and 429, contacts of relay 426 to ground at the armature of relay 404. Relay 628 locks in series with the winding of relay 426, the latter relay remaining normal. As hereinbefore described, relays 412 and 413 undergo their cycles of operation and release and impulses corresponding to the 10 first digit of the office code are transmitted to the receiving relays of the tandem sender 320. Since register relay 631 is normal no numerical impulse is transmitted during the 15 first impulse period. At the end of the first period, relay 406 operates and reverses the connection of the tip and ring conductors. During the second period, relay 632 being normal, no numerical impulse is sent. However, a circuit is completed from battery through the high resistance 671, left outer 20 front contacts of relay 406, thence by means of a circuit hereinbefore described in detail over the ring side of trunk 161 and 261, through contacts of switch 250, conductor 753, right outer contacts of relay 702, inner 25 front contacts of relay 703, winding of relay 706, conductor 756, returning by means of switches 250 and 200 to the ring conductor of trunk 264, left front contacts of relay 303, contacts of sender selector switch 310, 30 through impulse receiving relays in sender 320 (these relays being similar to relays 705, 708 and 709) returning through switch 310, right front contacts of relay 303, tip side of trunk 264, contacts of switches 200 and 250, conductor 757, front contacts of relay 701, conductor 759, contacts of switch 250, tip conductor of trunk 161, to ground at 35 relay 419 as already traced. Relay 706 being of the comparatively low resistance type is enabled to operate in series with the high resistance 671. The operation of relay 706 extends ground to the winding of relays 707 and 710, relay 710 alone operating. As noted hereinbefore, this light negative impulse is sent at the end of the second and 40 fourth pulsing periods. When relay 710 is thus operated, a circuit is completed from battery through the winding of relay 721, back contacts of relay 722, left front contacts of relay 713 and 714, left front contact of relay 710 to the grounded conductor 45 751. Relay 721 immediately locks in series with the winding of relay 722 to the grounded conductors 751 but relay 722 is meanwhile shunted and fails to operate. At the end of the second impulse period, relay 406 releases thus causing the release of relay 706 whereby the shunt is removed from relay 707 which now operates 50 in series with relay 710. When the light negative impulse is sent during the fourth period, relay 707 remains locked but relay 710 is shunted and releases. At the completion of the fourth period when relays 406 and 706 release, the locking circuit of relay 707 is broken which thereupon releases, removing the shunt from around the winding of relay 722 which now operates in series with relay 721. It is to be noted that these light negative impulses are not of a numerical nature but are sent to transfer the control of the impulse receiving relays in sender 310, as well as relays 707 and 710, to the successive registers. It will be understood that other code impulses are sent during the 55 various periods in accordance with the setting of the various registers 610, 620, etc. In a similar manner, the record on register 620 is transmitted by means of impulses to a corresponding register in the tandem sender 320. During the second impulse period corresponding to the transmission of this second digit, relay 723 operates while relay 724 remains normal and at the completion of the transmission of this digit, relay 724 operates 60 in series with relay 723. Thus, the sets of relays 721 and 722, 723 and 724, 725 and 726, 719 and 720, etc., in conjunction with the pulse counting relay 706 serve to count off the transmission of impulses to the tandem sender. It will be observed that because the receiving relays 705, 708 and 709 are ineffective during these latter operations, the transmission of impulses corresponding 65 to the setting of the thousandths register 640, 70 and the succeeding numerical registers 670, has no effect on registers 750, 740, 730, etc., the transmitted impulses causing the setting of the corresponding registers of the tandem sender 320. When the complete record has thus been transmitted to the sender 320, relay 758 is operated closing an obvious circuit for relay 702. The operation of relay 702 serves to bring about the release of the sender shown in Fig. 7, the marker shown 75 in the upper right hand corner of Fig. 5, sender connector 571, connectors 230 and 240, sender selector switch 250 and the vertical magnets 216 and 217. Connection through switch 200 is maintained by the 80 continued energization of the horizontal magnet 218 which is locked to the grounded sleeve conductor of trunk 264. When the complete record of the called line is registered in the sender 320, the sender connector 85 330 is operated and associates an idle marker as 340 with the said sender. The record of the office code in sender 320 is thereupon transferred to corresponding registers in the marker 340 and is therein translated 90 whereby a particular group of trunks including trunk 364 leading to the called office 350 is marked for selection. At this time also, frame connector 360 and trunk connector 370 are actuated, and marker 340 95 100 105 110 115 120 125 130

performs a test of the links in switch 300 and the trunks in the marked group. Assuming trunk 364 and link 365 to constitute the first available cross point then the 5 corresponding horizontal magnet 366 is operated and trunk 364 is seized. The seizure of trunk 364 results in the association at the called office 350 of a sender selector and an incoming sender, similar to sender selector 250 and the sender of Fig. 7 with the 10 said trunk. Thereupon, the numerical record of the called line designation is transferred from the registers of sender 320 to corresponding registers of the incoming 15 sender in the called office. The reception of the numerical record in the called office thereupon serves to control the operation of series of selective switches by means of which connection is completed with the wanted 20 line. The manner in which the tandem sender 320 receives code impulses and the manner in which the district switch 300 is actuated to select an outgoing trunk, are fully described in the copending application 25 of S. B. Williams and E. S. Gibson, Serial No. 645,011, filed June 13, 1923 to which application reference may also be had for a description of the manner in which the incoming sender shown in Fig. 7 and the associated marker are released following the 30 transmission of the complete designation to the tandem sender 320. Reference to this application may also be had for the manner in which the numerical record is retransferred from the tandem sender 320 to the 35 incoming sender at the called office 350 and also for the manner in which this record causes series of switches to operate to connect with the called line. When the complete 40 number of impulses have been sent from the calling office, the controlling apparatus including the sender selector switch 150, trunk connector 170, frame connector 180, the originating sender, the sender and associated 45 controlling apparatus at the intermediate office release, and when connection is completed between the calling and the called line, the sender and other controlling apparatus at the called office release. The application of S. B. Williams 50 and E. S. Gibson, Serial No. 645,011, referred to above describes in detail the manner in which the various senders and controlling apparatus in the calling office, tandem office and called office are released following the seizure of the called line.

In some instances a trunk may be selected at switch 160, which leads to an office where the incoming senders are not equipped with a preliminary register comprising relays similar to relays 711 and 713. In such cases when the office code is translated in the marker at the calling office, the translator 550 causes a relay 517 to operate, at the same

time grounding conductors 552 and 556. 65 An inspection of the circuits will reveal the fact that under these conditions class relays 424, 425, 429 and 625 remain normal while class relays 416 and 417 are operated. Therefore, when the sender is ready to send 70 out impulses, the first impulse to be sent will be in accordance with the setting of thousands register 640. Since the operating circuit for the cut-in relay 623 is opened at the right front contact of relay 429, relay 623 75 remains normal; instead, when the sender at the called office is attached and relays 418 and 419 operate in series, a circuit is completed from battery through the winding of relay 616, right back contacts of relay 626, 80 right inner back contacts of relay 424, right outer back contacts of relay 625, right back contacts of relay 429, contacts of relay 426, to ground at the contacts of relay 404. Relay 616 locks and associates the thousands 85 register relays 617, 618, etc., with the impulses mechanism of Fig. 4. Code impulses are thereupon sent to position the thousands register in the incoming sender at the distant office in the manner described in detail 90 in the application of S. B. Williams and E. S. Gibson, Serial No. 645,011, hereinbefore referred to. Similarly code impulses are sent in accordance with the setting of the succeeding numerical registers 670 whereby 95 the hundreds, tens and units registers of the incoming sender are positioned. The extension of the connection is then completed in the same manner as described in the Williams-Gibson application, Serial No. 645,011. 100

What is claimed is:—

1. In a telephone exchange system, a calling office, an office beyond adapted to function as a tandem office or as a local office, means for recording in said calling office the office code designation and numerical designation of a wanted line, means for transferring said recorded designations from said calling office to said office beyond, and means effective when said office beyond is to function as a tandem office for transmitting there-to from said first office a class indication prior to the transmission of any portion of said recorded designations. 115

2. In a telephone exchange system, a calling office, an office beyond adapted to function as a tandem office and as a local office, means for establishing a record in said first office in accordance with the complete designation of a wanted line, means for transferring a portion of said recorded designation from said calling office to said office beyond, and means effective when said office beyond is to function as a tandem office for transmitting thereto a distinctive digit prior to the transferral of the said recorded designation. 120 125

3. In a telephone exchange system, a call-

- ing office, an office beyond, means for establishing in said calling office a record in accordance with the office code and numerical designation of a wanted line, means for transmitting code impulses from said calling office to said office beyond the number and character of said impulses being determined by said recorded designation, and means dependent upon the location of said wanted line for transmitting from said calling office to said office beyond a series of distinctive impulses prior to the transmission of any of said code impulses.
4. In a telephone exchange system, a first office, a second office, a third office, a calling line in said first office, called lines in said second office, called lines in said third office, means in said second office for extending said calling line toward a called line in said second office said means being adapted to extend said calling line toward a called line in said third office, means for recording in said first office the designation of a called line, means for transferring said recorded designation from said first office to said second office, and means effective dependent upon the office in which said called line is located for transmitting from said first office to said second office a class of service indication by means of code impulses prior to the transferring of any part of said recorded designation.
5. In a telephone exchange system a first office, a second office, a third office, a calling line in said first office, called lines in said second office, called lines in said third office, means in said second office adapted to extend said calling line to a called line in either said second office or to a called line in said third office, means for recording in said first office the designation of a called line, means for transferring said recorded designation from said first office to said second office, and means in said first office effective dependent upon the office in which said called line is located for transmitting from said first office to said second office a special digit prior to the transferral of any of said recorded designations.
6. In a telephone exchange system, a first office, a second office, a third office, a calling line in said first office, called lines in said second office, called lines in said third office, means in said second office adapted to extend said calling line to a called line in either said second office or to a called line in said third office, means in said first office for recording the office code and the numerical designations of a called line, means for transferring the recorded numerical designations from said first office to said second office, means effective when said called line is in said second office for transmitting a preliminary digit from the first office to the second office, and means effective when said called line is in said third office for transmitting a different preliminary digit from said first office to said second office.
7. In a telephone exchange system, subscribers' lines, a calling office, an office beyond adapted to function as a tandem office and as a local office, register senders in the calling office and in the office beyond, means for recording in a register sender at the calling office the designation of a wanted line, means for transmitting series of code impulses in accordance with said recorded designation from the sender in the calling office to the sender in the office beyond, and means effective when the office beyond is to function as a tandem office for sending from the sender in the calling office to the sender in the office beyond a characteristic series of impulses as a class of service indication prior to the sending of impulses corresponding to any part of said recorded designation.
8. In a telephone exchange system, subscribers' lines, a calling office, an office beyond adapted to function as a tandem office and as a local office, register senders in the calling office, register senders in the office beyond each sender comprising a plurality of numerical registers and preliminary register, means for recording in a sender at the calling office the complete designation of the wanted line, means for transmitting series of code impulses corresponding to said recorded designation from the sender in the calling office to a sender in the office beyond, and means for sending from the sender at the first office to the preliminary register in said sender in the office beyond a series of code impulses as a class of service indication.
9. In a telephone exchange system, subscribers' lines, a calling office, an office beyond adapted to function as a tandem office and as a local office, a sender in said calling office comprising a plurality of registers to be positioned directly in accordance with impulses sent over a subscriber's line, and a preliminary register to be set independently of impulses transmitted over said line, means for sending from said calling office to said office beyond series of code impulses in accordance with the setting of said first mentioned registers and said preliminary register, and means at said office beyond effective dependent upon the impulses sent in accordance with the positioning of said preliminary register for determining whether said office beyond is to function as a tandem office or as a local office.
10. In a telephone exchange system, a calling office, an office beyond adapted to function as a tandem office and as a local office, a recording sender in the calling office com-

prising registers for recording digital designations and a preliminary register, both classes of registers consisting of relays, means dependent upon the setting of said digital registers for setting said preliminary register at the calling office, a recording sender in the office beyond comprising numerical registers and a preliminary register, means for sending code impulses through the contacts of the preliminary register at the calling office to set the preliminary register at the office beyond, and means effective dependent upon the setting of the preliminary register for determining whether the office beyond shall function as a tandem office or as a local office.

5   numerical designation of a wanted line and a preliminary register, a switch controlling marker in said calling office, means in said marker for receiving from said sender the record of the office code and for translating the same, means for selectively setting said preliminary register in accordance with said translated record, selective switches in said office beyond for extending connections to subscribers' lines therein and to subscribers' lines in the called office, means for sending code impulses from said calling office in accordance with the setting of said preliminary register alone to control the operation of one of said switches.

10   70   75   80

11. In a telephone exchange system, subscribers' lines, a calling office, an office beyond, a register sender in the office beyond comprising a plurality of numerical registers and a preliminary register, means for sending code impulses from a calling office independently of the numerical designation of a wanted line to position the preliminary register at the office beyond, means effective in one condition of said preliminary register for sending code impulses from the calling office to the sender at the office beyond, and means effective in another condition of the preliminary register for sending code impulses from the calling office directly through the sender at the office beyond.

15   85   90

12. In a telephone exchange system, a calling office, an office beyond, a called office, a register sender in the office beyond for controlling the completion of connections therein and for controlling the extension of connections to said called office, means for sending code impulses from the calling office to the office beyond to indicate to said office beyond the location of a wanted line, said code impulses being transmitted prior to the recording of any part of the designation of the wanted line in said register sender.

40   100   105

45   110   115

13. In a telephone exchange system, a calling office, an office beyond, a called office, a recording sender in said office beyond for controlling the completion of connections therein and for controlling the extension of connections to said called office, said sender comprising a series of registers to be set in accordance with the numerical designation of a wanted line and a class of service register, means for sending from the calling office impulses to position the class of service register to indicate to said office beyond the location of the wanted line, said impulses being received prior to the recording of any part of the designation of said wanted line in said sender.

50   120   125

55   120   125

14. In a telephone exchange system, subscribers' lines, a calling office, an office beyond, a recording sender in the calling office comprising a plurality of registers to be set in accordance with the office code and nu-

ing said second sender with the sender in the calling office.

18. In a telephone exchange system, subscribers' lines, a calling office and a sender therein, said sender having registers to be set in accordance with the office code and numerical designation of a wanted line and a class of service register, an office beyond, a recording sender in said office beyond comprising numerical registers and a preliminary register, means for sending code impulses in accordance with the setting of the class of service register at the calling office to position the preliminary register at the office beyond, said impulses being sent prior to the recording of the numerical designation of a wanted line in the sender at the office beyond, means effective in one condition of said preliminary register for transferring the numerical portion of said record from the sender at the calling office to the sender at the office beyond, and means effective in another condition of said preliminary register for transferring the complete record directly through the sender at the office beyond.

19. In a telephone exchange system, subscribers' lines, a calling office and a sender therein, said sender having registers to be set in accordance with the office code and numerical designation of a wanted line and a class of service register, an office beyond, a first recording sender in said office beyond, a second recording sender in said office beyond, means effective in one condition of said class

of service register for transferring the numerical portion of said record from the sender at the calling office to the first sender at the office beyond, and means effective in another condition of said class of service register for transferring the complete record directly through said first recording sender to said second recording sender.

20. In a telephone exchange system, a calling office, an office beyond, a first recording sender in said office beyond comprising a plurality of numerical registers and a class of service register, a second recording sender in the office beyond comprising office code and numerical registers, means for sending impulses in accordance with the office code and numerical designation of a wanted line from the calling office to the office beyond, means dependent upon the office wherein the wanted line is located for sending code impulses from the calling office to set the class of service register in said first recording sender, means responsive to one setting of said class register for sending code impulses to set the numerical registers in said first recording sender, and means responsive to another condition of said class register for sending code impulses directly through said first sender to set the office code and numerical registers of said second recording sender.

In witness whereof, I hereunto subscribe my name this 26th day of December A. D., 1924.

SAMUEL B. WILLIAMS.
